—o—
A. ROSENSTEIN.
CANE OR UMBRELLA HANDLE.

No. 20,143.

Patented Sept. 9, 1890

UNITED STATES PATENT OFFICE.

ALBERT ROSENSTEIN, OF LANCASTER, PENNSYLVANIA.

DESIGN FOR A CANE OR UMBRELLA HANDLE.

SPECIFICATION forming part of Design No. 20,143, dated September 9, 1890.

Application filed July 31, 1890. Serial No. 380,570. Term of patent 3½ years.

To all whom it may concern:

Be it known that I, ALBERT ROSENSTEIN, of Lancaster, in the county of Lancaster and State of Pennsylvania, have invented certain new and useful Improvements in Designs for Cane, Umbrella, or Parasol Handles; and I do hereby declare the following to be a full, clear, and exact description of the invention, such as will enable others skilled in the art to which it pertains to make and use it, reference being had to the accompanying drawings, which form part of this specification.

My invention relates to an improvement in designs for cane, umbrella, or parasol handles; and it consists in the novel shape and configuration of parts, whereby a pleasing and beautiful effect is produced, as will be more fully described hereinafter.

The accompanying photographic illustration represents my invention.

A represents the inner end of the handle, which has a number of ornamental figures or designs B extending in a line therewith. Extending diagonally around this straight portion of the handle are the three pairs of ribs or flanges C, at any suitable distance apart. Extending outward from the outer end of the handle are the two branches F G, one of which is much shorter than the other, and both of which are triangular in cross-section, and each has a series of depressions or recesses formed

in its two outer sides, while its inner side is made more or less convex and slightly corrugated. The shorter one of the two branches curves outward and ends in a slight volute or ball, while the other branch, which is much longer, is curved upward and outward from the handle and ends in a ball H. Placed upon the top of these two branches is the curved piece I, which tapers from one end toward the other, and which is about triangular in cross-section. The larger end tapers upward to a point, while the other terminates in the ball H.

A handle constructed as here shown and described presents a unique and beautiful appearance and adds greatly to the attractiveness of the article to which it is applied.

Having thus described my invention, I claim:

A design for cane, umbrella, or parasol handles, as herein shown and described, consisting of the straight portion having a series of rings extending around it, the two branches of unequal length, and the figure placed upon the ends of the branches, as set forth.

In testimony whereof I affix my signature in presence of two witnesses.

ALBERT ROSENSTEIN.

Witnesses:

E. P. ELLIS,
ALLEN S. PATTISON.
